BOTTLE CAP AND CLOSURE

Bernard P. Lasky, Beverly Hills, Calif.

Application October 3, 1941, Serial No. 413,509

1 Claim. (Cl. 215—79)

This invention relates to bottle closures and it consists in the constructions, arrangements and combinations herein described and claimed.

It is the cardinal object of the invention to provide a bottle closure or cap which may be made as an integral part of the bottle, permitting the dispensing of a liquid, yet preventing refilling of the bottle. It is a further object of the invention to provide a combined dispensing cap and closure cap therefor, the latter effectively sealing the bottle when applied, yet readily removable for dispensing of a liquid from the bottle, and further affords a protection to the dispensing cap during transportation.

Additional objects, advantages and features of invention will be apparent from the following description considered in conjunction with the accompanying drawing, wherein

Figure 1 is a fragmentary elevation of a bottle having my invention applied thereon

Figure 2 is a similar view with the closure cap removed.

Figure 3 is a view similar to Figure 1, partly in section.

Figure 4 is an elevation of the dispensing cap.

There is illustrated a bottle 10 having an exteriorly threaded neck 11, as clearly shown in Figures 2 and 3. It should be noted that the threads 12 stop short of the upper end of the neck a substantial distance, and immediately above the uppermost thread portion there is formed a circumscribing groove 13.

A dispensing cap 14 is provided, having a semi-spherical body 15 terminating in an annular skirt 16. The skirt 16 is of a diameter so as to snugly fit around the neck of the bottle and of a length so as to present the lower edge above the groove 13, where it may be turned thereto for securing of the cap to the neck. The cap 14 may be formed from metal, plastic or glass, and obviously may be cemented to the neck for securing if desired.

The semi-spherical body 15 is perforated, as at 17, the perforations being quite small but of sufficient number to permit ready flow of liquid therethrough.

A vent tube 18 is integrally formed with the body 15, of a length extending well into the neck, as shown.

A closure cap 19 is employed for sealing the bottle when not in use or during shipment, which consists of a body portion 20 having a shape conforming to that of the dispensing cap 14, but of greater dimensions, so that the cap 19 will snugly seat upon the cap 14.

A cork insert 21 is positioned within the cap 19, adapted to snugly engage the dispensing cap 14 when the threaded skirt portion 22 is engaged upon the threaded neck of the bottle. The cork insert 21 is semi-spherical in shape complementary to the dispensing cap and the closure cap and of such size as to overlie and close the perforations 17 when the cap 19 is fully engaged upon the neck and the cap 14.

The cap is particularly well suited to use in dispensing liquors since a customer may be sure that an inferior grade of liquor has not been substituted, and in use, the closure cap 19 is removed, and the bottle held over the glass to be filled, so that perforations 17 will discharge the liquor thereinto. Air will enter through the tube 18, permitting free flow of the liquor.

While I have specifically shown and described the invention, this is by way of illustration only and I consider as my own all such modifications in structure as fairly fall within the scope of the appended claim.

I claim:

- 20 30 A dispensing cap for a bottle having a threaded neck and a groove above the uppermost thread, said cap having a semi-spherical upper end and a depending skirt portion adapted to snugly fit the bottle neck, the skirt being permanently secured at its lower end within the groove, said cap further having a plurality of apertures formed in a side thereof, a vent tube on the cap of a length to be extended into a bottle neck, a closure cap threaded and engaged with the threads of the bottle neck and having a shape corresponding to the first cap, and a similarly shaped cork in the closure cap constructed and adapted to overlie the apertures of the first cap when the closure cap is fully engaged upon a bottle neck, but of a depth stopping short of the lower edge of the skirt portion a substantial distance.

BERNARD P. LASKY.
